DEGREASING METAL STRIP

William Edward Booth, Runcorn, England, assignor to Imperial Chemical Industries Limited, a corporation of Great Britain

Application February 12, 1940, Serial No. 318,660
In Great Britain February 20, 1939

12 Claims.

(Cl. 202—170)

This invention relates to degreasing metal strip by treating it with a volatile solvent.

It has previously been proposed to degrease metal strip by treating it with the vapour of a volatile solvent. In order that solvent losses during such a process may be minimized it is essential that the strip shall be dry when leaving the apparatus. When degreasing metal castings and similar heavy articles, they are usually dried by keeping them, while still hot, in the solvent vapour for a short time. This method is not effective for metal strip because of its low heat capacity per unit length, and, indeed, drying metal strip which has been degreased in solvent vapour is a problem peculiar to that material, particularly when the degreasing process is a continuous one. These drying difficulties, together with the above mentioned requirement of minimizing solvent losses, have hitherto set a limit to the speed at which the metal strip can be passed through such a solvent degreasing apparatus.

One method for treating metal strip with volatile solvent has been described, in which the strip is withdrawn through an almost horizontal tunnel-like enclosure above the vapour level and having a condensing coil adjacent to its lower surface. Such a device has the disadvantage of increasing the overall length of the plant, and is not entirely satisfactory since solvent laden air tends to escape at the exit of the tunnel, and this tendency can only be counteracted by running the metal strip through the plant at low speeds.

The apparatus of the present invention, on the other hand, is capable of operation at much greater speeds than have hitherto been feasible, while entailing smaller solvent losses.

According to the present invention, therefore, an apparatus for the continuous degreasing of metal strip by treating it with a volatile grease solvent whose vapour is heavier than air, comprises a closed vessel having an entrance and exit for the metal strip, means for maintaining a solvent vapour zone within the said vessel, means for introducing metal strip into said vessel, a tube at the exit for the metal strip extending vertically or substantially vertically above the degreasing vessel and provided with cooling means, and means for withdrawing the treated metal strip from the vapour zone through said tube.

Preferably the exit is above the vapour zone and the tube extends into the plant below the vapour level; preferably also, staggered rollers or

fixed smooth rods are disposed at or near the point where the strip leaves the vapour zone, so that each surface of the strip contacts at least one roller or rod in passing to the exit tube.

5 In addition to the solvent vapour zone, one or more liquor treatment compartments, or a spray treatment compartment may also be provided, placed before the vapour compartment in the path of the strip.

10 The entrance for the metal strip may be merely a slit in the casing above the solvent vapour level, as determined, for example, by cooling coils around the sides of the vessel, rollers or guides being provided to cause the strip to pass down into and through the degreasing zone. A winding mechanism may be provided beyond the exit side of the apparatus to roll up the degreased strip and pull it through the apparatus. Alternatively, the strip may pass between a pair of rollers at or beyond the end of the exit tube which grip the strip and which are driven by suitable means so as to pull the strip out of the apparatus as they rotate. We find it preferable, however, to provide at the entrance a device similar to that which we provide at the exit, that is to say, a tube fitted with cooling means and extending upwards from the degreasing vessel, preferably to approximately the same height as the tube at the exit. Alternatively, the strip may be introduced and removed through the same tube, suitable rollers or guides being provided to cause the strip to pass through the vapour zone and the liquor or spray compartments where such are included.

15 20 25 30 35 In any of the modifications of our invention the tubes may be pivoted at the base to facilitate threading the strip through the apparatus.

In some cases, particularly when the degreasing apparatus comprises a vapour compartment only, it is advantageous to give the strip a rinse with pure solvent shortly before its removal from the vapour zone in order to remove adherent insoluble solids; where, as is almost invariably the case, condensing coils around the inside walls of the vessel are used to limit upwardly the vapour zone, this may be done by providing below the level of the coils and preferably near the exit for the metal strip, a horizontal trough-shaped vessel having at its lowest part a slit through the strip passes in an upward direction, and feeding to the trough pure solvent, e. g. condensate from the condensing coils. Both sides of the strip are thus washed with the stream of solvent which will flow through the slit counter-

current to it, and insoluble matter will be washed off.

In one form of our invention the apparatus comprises a closed vessel, vaporising means, e. g. a sump fitted with heating coils, for maintaining a solvent vapour atmosphere in the vessel and cooling coils in the upper part to condense vapour and return it to the sump or other vaporizer. The vessel has a slit at one end above the vapour level to admit metal strip, and at the other end a vertical water-jacketed tube extending above the vessel. The inner walls of the tube are continued below the top of the vessel to just below the level of the cooling coils, and are expanded into a small chamber between the cooling coils and the top of the vessel to contain three horizontal parallel fixed rods one above other, the middle one being displaced in a vertical plane relative to the other two. Rollers are also provided at the upper end of the vertical exit tube and within the degreaser to guide the strip through the vapour zone. A winding mechanism beyond the apparatus winds up the degreased strip and serves as a means for pulling it over the rollers.

In using this apparatus the strip is threaded through the apparatus, passing zig zag between the rods at the base of the exit tube, so that both surfaces make contact with a rod. Supplies of cooling water are turned on to cooling coils and water jacket, and vapour is generated. As the strip is passed through the apparatus the vapour condenses on it, and the condensate dissolves the grease; the majority of the solvent then falls back into the sump. As the strip rubs against the rollers most of the condensate still adhering is removed, leaving but a thin film to be carried into the jacketed tube. The strip being still practically at the temperature of the vapour this film is rapidly evaporated, to be recondensed on the cold water jacket and fall back into the vapour zone. The vertical position of the tube ensures that heavy solvent-laden air will not remain in the tube and interfere with the further evaporation of solvent adhering to the strip, while because the solvent vapour is so much denser than air the continuation of the jacket into the vapour zone creates a seal which prevents through draughts of air being set up which would entrain solvent vapour and carry it out of the apparatus.

A further form of our invention, including a tube at both entrance and exit, will now be more particularly described with reference to the accompanying drawing illustrating a vertical section of such an apparatus.

In this drawing the closed vessel 1 has a sump 2 in its lower part provided with a steam coil 3 by which solvent can be vaporized; around the inside walls of the upper part of the vessel are condensing coils 4 which can be provided with a cooling liquid by means not shown. Immediately beneath coils 4 is a trough 5 to collect condensate from the coils. From one end of the vessel 1 a jacketed tube 6 extends vertically upwards and has an inlet and outlet 7, 7 by which cooling liquid, e. g. water or brine, can be circulated through the jacket. At the other end of the vessel is a second similar jacketed tube 8 having an inlet and outlet 9, 9, by which cooling liquid can be supplied to the jacket; the tube extends vertically upwards to substantially the same height as the first tube. As shown on the drawing the cross-sectional areas of tubes 6 and 8 are relatively restricted as compared to the

lengths of the tubes. Tubes 6 and 8 are pivoted at 17 to facilitate the threading of the strip 16. In their normal position the tubes form a vapour-tight seal at the junction with vessel 1. By means of flanged pulleys 18 the strip can be fed down through tube 6 into the vapour zone and out again through exit tube 8 after passage through the vapour zone. Tube 8 has an extension 11 reaching downwards to the level of the bottom of the condensing coils, and within extension 11 are three horizontal staggered rollers 12 one above the other. Immediately below the extension 11 is a V-shaped trough 13 having a slit 14 at the angle of the V to which condensate from trough 5 can be fed via plate 15 serving both as a support for trough 13 and a surface over which solvent can flow to it. A winding apparatus (not shown) is provided to coil up the strip as it leaves the apparatus, and to pull through further quantities of the strip to be treated.

In using the apparatus the strip 16 is threaded down tube 6 which, like tube 8, can be turned about pivots 17 as desired to facilitate this operation; the strip is then passed under the pulleys 18 within the degreasing compartment, threaded through slit 14 in trough 13, between rollers 12 so that both surfaces contact the rollers, up through tube 8 and over the remaining pulley 19 to the winding apparatus which pulls the strip through the degreasing apparatus when the latter is in operation. The supply of cooling liquid to the jackets of tubes 6 and 8 and to coils 4 is then commenced and the solvent vapour zone set up by boiling solvent in sump 2 by coil 3. Degreasing then proceeds as the strip is pulled through, the main degreasing proceeding as the strip passes between the pulleys 18 within the vapour zone, but a supplementary washing of the hot strip being applied as it passes through slit 14 countercurrent to fresh condensate flowing from trough 5 over surface 15 into trough 13 and thence down through slit 14 to fall into sump 2. As the strip passes over rollers 12 adherent solvent is removed, leaving at most a thin film on the strip as it enters the tube 8. Since the strip will still be substantially at the temperature of the vapour this film will evaporate rapidly and be recondensed on the cold water jacket to fall back into the vapour zone. The vertical position of the tube and the action of the cold water jacket ensure that heavy solvent vapour-laden air will not remain in the tube and impede the evaporation of solvent adhering to the strip; thus the whole drying process is accelerated, and since it is this which in practice sets a limit to the speed at which degreasing can be carried out, the operation as a whole can be carried out more rapidly than has hitherto been possible.

Since extension 11 of tube 8 extends below the solvent vapour level a seal is formed by the heavy solvent vapour, and through draughts of air cannot be set up entraining vapour and carrying it out of the apparatus; this possibility is still further diminished by the jacketed tube 6 at the entrance, since any solvent tending to diffuse up into this tube will be condensed on the jacket; moreover as the tubes 6 and 8 are the same height, balanced columns of air in the two tubes are created which balance again diminishes any tendency for currents of air to circulate through the apparatus.

I claim:

1. Apparatus for the continuous degreasing of metal strip by treatment with a volatile grease

solvent the vapour of which is heavier than air, comprising a closed vessel having an entrance and an exit for the metal strip, means for maintaining a solvent vapour zone within the said vessel, means for introducing metal strip into the vessel, a tube at the exit provided with cooling means and extending substantially vertically upwards from the said vessel, said cooling means comprising a water jacket surrounding said tube above the level of said vessel, and means for withdrawing the treated metal strip from the vapour zone through the said tube.

2. Apparatus according to claim 1 in which the tube through which the metal strip is withdrawn extends downwards into the vessel to a point below the solvent vapour level.

3. Apparatus according to claim 1 in which staggered guides are disposed at or near the point where the strip leaves the vapour zone so that each surface of the strip makes contact with at least one such guide in passing to the exit tube.

4. Apparatus for the continuous degreasing of metal strip by treatment with a volatile grease solvent the vapor of which is heavier than air, said apparatus comprising a closed vessel having an entrance and an exit for the metal strip; means for maintaining a solvent vapor zone within said vessel; means for introducing metal strip into said vessel; a tube positioned at the exit, said tube extending substantially vertically upward from said vessel and being provided with cooling means consisting of a water jacket surrounding said tube above the level of said vessel; means for withdrawing the treated metal strip from the vapor zone through said tube; a liquid solvent receptacle positioned within said vapor zone, said receptacle being provided at its bottom with an opening for passing the metal strip upwardly therethrough and for simultaneously draining solvent downwardly therethrough, whereby to effect countercurrent washing of said strip with said solvent; and means for delivering pure solvent to said receptacle.

5. Apparatus for the continuous degreasing of metal strip by treatment with a volatile grease solvent the vapour of which is heavier than air, comprising a closed vessel with means for maintaining a solvent vapour zone therein, an entrance tube extending substantially vertically upwards from the said vessel provided with cooling means and with means for introducing metal strip into the vessel through the said entrance tube, and an exit tube similarly extending substantially vertically upwards from the vessel provided with cooling means and with means for withdrawing the metal strip from the vapour zone through the said exit tube, both of said cooling means comprising water jackets surrounding the respective tubes above the level of said vessel.

6. Apparatus according to claim 5 in which at least one of the upwardly-extending tubes extends downwards into the vessel to a point below the solvent vapour level.

7. Apparatus according to claim 5 in which staggered guides are disposed at or near the point where the strip leaves the vapour zone so that each surface of the strip makes contact with at least one such guide in passing to the exit tube.

8. Apparatus for the continuous degreasing of

metal strip by treatment with a volatile grease solvent the vapor of which is heavier than air, said apparatus comprising a closed vessel with means for maintaining a solvent vapor zone therein; an entrance tube extending substantially vertically upwards from said vessel and provided with cooling means consisting of a water jacket surrounding said tube above the level of said vessel and with means for introducing metal strip into the vessel through the said entrance tube; an exit tube similarly extending substantially vertically upwards from the vessel and provided with cooling means consisting of a water jacket surrounding said tube above the level of said vessel and with means for withdrawing the metal strip from the vapor zone through the said exit tube; a liquid solvent receptacle positioned within said vapor zone, said receptacle being provided at its bottom with an opening for passing the metal strip upwardly therethrough and for simultaneously draining solvent downwardly therethrough, whereby to effect countercurrent washing of said strip with said solvent; and means for delivering pure solvent to said receptacle.

9. Apparatus for the continuous degreasing of metal strip by treatment with a volatile grease solvent the vapour of which is heavier than air, comprising a closed vessel with means for maintaining a solvent vapour zone therein, a tube extending substantially vertically upwards from the said vessel provided with cooling means and with means for introducing metal strip into the vessel through the said tube and for withdrawing the strip after treatment through the same tube, said cooling means comprising a water jacket surrounding said tube above the level of said vessel.

10. Apparatus according to claim 9 in which the upwardly-extending tube extends downwards into the vessel to a point below the solvent vapour level.

11. Apparatus according to claim 9 in which staggered guides are disposed at or near the point where the strip leaves the vapour zone so that each surface of the strip makes contact with at least one such guide in passing out of the vessel into the upwardly-extending tube.

12. Apparatus for the continuous degreasing of metal strip by treatment with a volatile grease solvent, the vapor of which is heavier than air, said apparatus comprising a closed vessel with means for maintaining a solvent vapor zone therein; a tube extending substantially vertically upwards from the said vessel; cooling means for said tube consisting of a water jacket surrounding said tube above the level of said vessel; means for introducing metal strip into the vessel through the said tube and for withdrawing the strip after treatment through the same tube; a liquid solvent receptacle positioned within the said vapor zone, said receptacle being provided at its bottom with an opening for passing the metal strip upwardly therethrough and for simultaneously draining solvent downwardly therethrough, whereby to effect countercurrent washing of said strip with said solvent; and means for draining pure solvent to said receptacle.

WILLIAM EDWARD BOOTH.
